DAVID G. BRANDT, OF WESTFIELD, NEW JERSEY, ASSIGNOR TO DOHERTY RESEARCH COMPANY, OF NEW YORK, N. Y., A CORPORATION OF DELAWARE

HEAT-INTERCHANGING APPARATUS

Application filed February 6, 1928. Serial No. 252,092.

This invention relates to improvements in heat interchange apparatus, and more particularly to heat interchange apparatus of the recuperator type designed for use in effecting efficient indirect heat interchange between two confined bodies of fluid flowing continuously across opposite faces of a heat conductant partition wall or diaphragm.

The capacity of a heat interchange apparatus of this type is dependent particularly on the extent of the heat conductant diaphragm surface between the two bodies of fluid undergoing indirect heat interchange, and on the rapidity and uniformity with which the bodies of fluid are circulated in contact with the surfaces of the diaphragm.

An object of the present invention is to provide heat interchange apparatus of the recuperator type having a large heat interchanging heat conductant diaphragm surface capable of withstanding substantial pressure differentials obtaining between the heating and heat receiving fluids passed over opposite faces thereof.

Another object of the invention is to provide heat interchange apparatus of the recuperator type in which the heat conductant diaphragms form long sinuous pressure resistant flues of extensive surface which may be assembled in compact and accessible form within an outer enclosed cylindrical shell.

More specific objects of the invention are: To provide a recuperator assembly of the above character so designed as to permit ready access through the outer shell to every portion of the inner flues; to so construct the inner flues of the recuperator as to provide long devious paths for the fluid to be heated and a proportionately large heat transfer surface per unit of space occupied separating the fluid to be heated from the heating fluid; to provide a form of high pressure resistant recuperator flue which can be assembled from a plurality of uniformly shaped individually removable segments into a compact nest of annular cross section; to provide recuperator flue segments of uniform, sinuous and compact shape that can be readily cast in molds, assembled in multiple into coils and

nests of annular cross section, and cleaned without dismantling.

With these and other objects in view, the invention consists in the improved heat interchange apparatus hereinafter described and more particularly defined in the claims.

The various features of the invention are illustrated in the accompanying drawings, in which:

Fig. 1 is a view in vertical section, with parts broken away, of the upper part of a cylindrical dephlegmator column in which there is incorporated a recuperator assembly illustrative of a preferred form of embodiment of the present invention, taken on the line 1—1 of Fig. 2;

Fig. 2 is a cross section of the recuperator, taken on the line 2—2 of Fig. 1;

Fig. 3 is an enlarged plan view of one of the flue or tube segments which, assembled in multiple, make up the sinuous annular recuperator flues or flue sections shown in Fig. 2;

Fig. 4 is a side elevation of the flue segments shown in Fig. 3;

Fig. 5 is a plan view of one of the U-shaped flue segments shown in side elevation in Fig. 1 as connecting two adjacent vertically spaced tiers of annular sinuous flue coils in the assembled recuperator.

Fig. 6 is an end elevation of the U-shaped flue segment shown in Fig. 5.

According to the present invention the warmer and cooler fluids between which a heat interchange is to be affected are caused to flow, usually under pressure, in sinuous or baffled streams separated by relatively thin but strong heat conductant diaphragms through which the interchange of heat takes place. The heat interchanging diaphragm is preferably formed into one or more long sinuous flues through which one of the fluids flows, a number of restricted passages being formed around and among the bends and straight portions of said flues through which the other fluid flows. The flues are in turn mounted in outer enclosed, preferably cylindrical, casings or shells capable of withstanding the pressures under which the fluids are supplied, in such a manner as to be accessible.

for cleaning or repairs without being removed from the shell.

The recuperator has been illustrated as incorporated in the upper part of a dephlegmator column of a type used in the fractional distillation of petroleum oils and like fluid mixtures, and accordingly it will be assumed in the interests of clarity in the following description that the recuperator is to be used for heating oil in the liquid state as it is passed downwardly through the inner flues of the recuperator by indirect heat interchange with hot oil vapors and gases passed upwardly through the recuperator and around the flues. It will be understood, however, that the recuperator is not limited to such use, but on the contrary is applicable generally for effecting indirect heat interchange between any two bodies of fluid passed in either direction therethrough in contact with opposite faces of the heat conductant flue-shaped diaphragms.

In the accompanying drawings (Fig. 1) the numeral 10 designates the integral closed cylindrical outer shell and end closures of the dephlegmator column which also serve as the outer shell of the recuperator forming the subject of the invention. The recuperator shell 10 is preferably constructed of heavy metal capable of withstanding high internal pressures and may advantageously be lined, externally or internally or both, with some good heat-insulating and/or corrosion-resistant material (not shown). A manhole entrance 12, closed by a removable cover 14, is provided in one end of the shell 10 in position to afford ready access from outside the shell to a passage 16 extending through the recuperator section of the dephlegmator along its longitudinal axis (Fig. 2) as far as the top tray or bubble plate 18. From this point access is had to the lower trays of the dephlegmator and to lower tiers or coils E of the recuperator flue which are mounted between the trays of the dephlegmator (shown in Fig. 1) through combined reflux overflow and gas and vapor uptake pipes 20. A gas and vapor offtake 22 leads off from the top of the recuperator adjacent the manhole opening 12, and one or more pipes 24 (two are shown in Fig. 1) serve to introduce oil (or other fluid) to be heated from some outside source through the shell 10 and into the first of a connected series of W-shaped tube sections 26, a plurality of which when assembled end to end make up continuous flues 28, the walls of which comprise the heat conductant diaphragms of the recuperator.

The flues 28 (Figs. 1 and 2) are disposed in the recuperator structure in the form of a nest of vertically separated and closely spaced connected tiers A, B, C, D, E, etc.; each tier lying in a plane at right angles to the longitudinal axis of shell 10 in the form of an

annular sinuous coil disposed concentrically about the axial manhole passage 16. Each of the tiers A, B, C, D, etc., comprises a plurality of the tube sections 26 assembled end to end. In the recuperator design illustrated in the drawings two continuous enclosed flues 28 are shown for conducting oil to be heated through the recuperator. Each flue 28 is supplied with oil by one of the two pipes 24, and each of the horizontally placed tiers A, B, C, D, E, etc. of each pair of flues is semi-circular in form, occupying in the assembled recuperator substantially one-half the annular space between the central opening 16 and the inner lining of the shell.

Each of the W-shaped tube sections 26 embodies in an integral structure two substantially 90° bends 30 and 32 disposed back to back, one on the open end of each of two outside legs 34 and 36 of the structure, together with three return or U-bends 38, 40 and 42 successively disposed in the structure and with their appurtenant connecting legs 44 and 46 forming a closed connection between the ends of legs 34 and 36 opposite those on which bends 30 and 32 are placed. The two outside U-bends thus face in one direction and form the base of the W-shaped structure while the inside U-bend 40 faces in the opposite direction and lies in the center of the structure. The longitudinal axis through the center of the W-shaped tube section 26, including all of its appurtenant legs and all of the five bends, lies in a single plane. The outer legs 34 and 36 are preferably of substantially equal length, and in the assembled recuperator the substantially right angle bends 30 and 32 are disposed at opposite ends of the legs 34 and 36 in the periphery of passage 16, while the return bends 38 and 42 lie in an arc paralleling and closely spaced from the inner periphery of shell 10. The return bends 38 and 42 lie in closely spaced but not abutting relationship, and the legs appurtenant thereto are disposed in a closely spaced relationship approaching the parallel but converging slightly in the direction of the open top of the structure, thus imparting a roughly isosceles triangle form to the structure viewed as a whole. While the longitudinal axes of the outer legs 34 and 36 of the sections 26 as they are illustrated converge toward a point located some distance beyond the bends 30 and 32 at the open ends thereof (such point lying in about the longitudinal axis of the shell 10 in the assembled recuperator) the backs of the bends 30 and 32 are not brought by such convergence into abutting relationship, though they are brought into a closely spaced or compact relationship. It will be observed that legs 34 and 36 are somewhat longer than the appurtenant legs 44 and 46 of the inner return bend 40, with the result that bend 40 lies some distance from bends 30 and 32 and nearer the base of the

structure formed by bends 38 and 42. In the assembled recuperator all of the legs 34, 36, 44 and 46 of each W-shaped tube section 26 lie in closely spaced relationship in substantially radial axes diverging from and at right angles to the longitudinal axis of shell 10.

Each W-shaped tube section 26 is preferably formed by casting it as an integral unit from material such as cast iron, brass or other relatively strong heat-conductant pressure- and-corrosion-resistant substance. In casting sections 26, openings 48 are preferably left in the mold at the back of each of the U-bends 38, 40 and 42 of the section in order to accommodate supports for the refractory core which is employed in the casting operation. After the casting has been completed and this core has been removed the holes 48 thus left in the casting are drilled to a suitable uniform size and tapped, and plugs or equivalent closures 50 are inserted and sealed in place therein.

Since one of the principal features of design of the W-shaped tube sections 26 is to provide a heat-interchanging surface of proportionately large area per unit of space occupied, it is sometimes advantageous to embody in the outer legs 34 and 36 thereof angles or equivalent moderate curvatures 52, with the object of drawing their free ends more closely together above the inner return bend 40 to thereby reduce the cross-sectional area of the spaces 54 lying between the outer and inner legs of the structure. For the same reason the inner legs 44 and 46 appurtenant to the return bend 40 are disposed in compact closely spaced relationship with the object of reducing as far as practicable the cross sectional area of spaces 56 lying therebetween. The preferred form of tube section 26 illustrated in the drawings has a shape resembling that of the letter W except that the outer legs 34 and 36 depart somewhat from the analogy with the letter W by diverging toward rather than away from the base of the structure.

Bolting ears 58 or their equivalents are formed at intervals about the circumference of each of the open ends of sections 26 as an integral part thereof, and spacer bosses 60 are also preferably cast as an integral part of these sections at points immediately above and/or below the return bends 38, 40 and 42 or at other suitable points of the structure.

Each of the tiers A, B, C, D, E, etc., composed of connected W-shaped sections 26, is in turn connected to the tier immediately above or below the same by an especially designed return bend 64 (see Figs. 1, 5 and 6), such bends in the assembled recuperator lying in a vertical plane at right angles to the horizontal plane of the tiers which it connects. Two right angle or substantially 90° tubular bends 66 are formed as an integral part of the bends 64, one on the open end of each of its legs

68, the open faces of the bends 66 being faced in a horizontal direction at right angles to the vertical plane occupied by the return bend in the assembled recuperator. Bolting ears 58 are formed as an integral part of the bends 66 thereby affording means for attaching the return bend section 64 to the open ends of the first and last in the series of W-shaped sections 26 comprising the respective tiers to be connected. These return bends 64 are preferably formed of cast metal in much the same manner as that employed in forming sections 26, openings 48 being left at the back of the return bend which are later tapped and sealed with plugs 50.

While the foregoing description sets forth in more or less detail the preferred shape of the tube sections 26 and the preferred number and relative positions of the bends and connecting legs embodied in their structure, it will be evident that such tube units may be formed in other ways than that described and may embody bends and appurtenant straight or curved legs assembled in an integral or multiple part tube section having a preferably uniform shape more or less closely analogous to that of the letters V and W, without departing from the spirit of the invention. The tube sections 26 with their bends and appurtenant connecting legs are designed to compactly fill the area of an annulus segment. The widest part of each of the preferred form of W-shaped tube sections 26 illustrated lies in the plane of the longitudinal axes passing through the tubes which form the section and is measured by the distance between the outsides of the two outer return bends 38 and 42 forming the closed base of the section, and the maximum width of the section is practically limited to a dimension which will permit insertion of the section as a unit into the shell 10 through the manhole 12. The size and form of the unit flue section also depends somewhat upon the size and weight of the flue of which these sections form a part. In the same way the maximum allowable width of each of the return bends 64 is preferably such as to allow of its insertion as a unit through the manhole opening 12 for assembly within the shell 10.

In assembling the recuperator the W-shaped tube sections 26 and the return bends 64 are inserted into the shell 10 through the manhole 12, and are then connected in end to end relationship in the manner illustrated to form in order the superimposed tiers E, D, C, B, A connected by the return bends 64. In case the sections 26 are to be assembled to form two continuous flues 28 through the recuperator, the nest of tiers A, B, C, D, E, which in assembled form make up each of the flues occupies about one half the annular space lying between the central opening in the shell and the inner periphery of the shell

(see the drawing). If on the other hand all of the sections 26 and bends 64 are to be assembled in the form of only one continuous flue 28, the nest of tiers A, B, C, D, E, etc. will occupy all the annular space between the opening 16 and the inner periphery of the shell. It will be understood that if desired the sections 26 and return bends 64 may be assembled into three, four or even 10 more continuous flues 28 traversing the length of the recuperator.

The opposite open ends of each of the W-shaped sections 26 and of each of the return bends 64 are provided respectively with male 15 and female joints comprising respectively annular noses 69 and sockets 70 to fit said noses (Fig. 3). Sealing rings or gaskets of asbestos, soft metal or the like may be disposed between the opposed surfaces of the 20 nose 69 and socket 70 making up the joint between the adjacent flue sections, and sections 26 and 64 may then be drawn and held rigidly together by bolts 72 passed through the ears 58 on the outside of each of the opposed connected faces of the sections. Alternatively such connections may be made by forming sockets similar to, but somewhat deeper than, the socket 70 illustrated, on both 25 open faces of each tube section, and by then drawing the sections together over a tight fitting sleeve collared by said sockets in the opposed ends of the adjacent sections 26 and welded or swedged into place (not shown).

Referring more particularly to Figs. 1 and 35 of the accompanying drawings, one of the heat interchanging fluids, preferably the cooler heat receiving fluid, for example oil, is admitted to the upper end of the shell 10 through the inlet pipes 24 and flows in a de- 40 vious horizontal path through the tube sections 26 making up the upper tiers A of the two continuous flues 28 extending through the recuperator in the direction of the arrows (see Fig. 2). After traversing the semi- 45 circular devious horizontal path occupied by the tiers A, the oil passes downwardly through the first return bends 64 into the underlying tiers B of the recuperator flues and follows a devious path through the sections 26 50 composing tiers B in a reverse horizontal direction to the path followed in traversing tiers A. From tiers B the oil passes downwardly into tiers C through the connecting return bends 64 and passes through tiers C in 55 horizontal paths paralleling those previously traversed in tiers A. From tiers C the oil passes downwardly into tiers D and after traversing the same again passes downwardly 60 into tiers E, and so on through the recuperator. In thus passing through the flues 28 of the recuperator the oil is rapidly heated by indirect transfer of heat abstracted from the heating fluids through the walls of the flues 65 and is finally removed at the lower end of the

recuperator through an outlet pipe (not shown).

The hot gases or vapors constituting the heating fluid enter the recuperator by way of uptake pipes 20 and flow upwardly in divided streams through the spaces and passages lying between each of the tiers A, B, C, D, E and the spaces 54 and 56 lying between and around the legs of the W-shaped tube sections composing the recuperator flues. In 70 thus passing through the recuperator the heating fluid is rapidly cooled by contact with the outside walls of the flues 28, with resultant indirect heat transfer to the fluid receiving heat as it passes through said flues; the thus cooled gases and vapors being finally received at the upper end of the shell 10 and removed through the outlet 22. In order to prevent the heating fluid from passing upwardly through the central aperture 16 75 formed in the major axis of the recuperator shell 10, a deflector 74 having an end closure 76 over its top is mounted in the opening 16. The deflector 74 serves to blank off the passage 16 and thus prevent the heating fluid from by-passing the passages 54 and 56 surrounding the flues carrying the heat receiving fluid. The deflector 74 is preferably constructed in three or more segments 78 having 80 inwardly extending lugs 80 (Fig. 2) which are suitably drilled to enable segments 78 to be bolted together. By building the deflector in segments it can be readily inserted into the shell through the manhole opening 90 85 and thereafter assembled in place.

In the drawings the tubes and tube sections of which the flues are composed have been illustrated as having a somewhat elliptical cross section with the major axis lying in a vertical plane. The purpose of this design is to provide a tube construction which is strong and which at the same time lends itself to close spacing of the legs and bends making up the tube sections 26, thereby providing a larger heat transferring surface per 95 unit of space occupied.

As indicated above, the cross sectional area of the opening 16 is preferably such that it will permit access to every portion of the recuperator for the purpose of cleaning, replacing or repairing each individual segment of the assembled flues. When access to the flues of the recuperator is desired the closure 76 of the deflector 74 is first removed and the rest of the deflector is then removed or placed to one side after dismantling it into its several sections 78. If it is desired to clear the flues this can be readily accomplished without disconnecting the individual flue sections 26 simply by drilling out or otherwise removing the plugs 50 in the ends of the inner return bends 40 of each section and removing the dirt or refuse secured by the cleaning operation through the openings 48 thus exposed. The depth of the space 56 between the periph- 100 105 110 115 120 125 130

ery of opening 16 and the opening 48 in the end of the inner return bends 40 of the section 26 is sufficient to permit insertion and manipulation of drill spindles and other tools employed in removing plugs 50 and in cleaning the tube sections or repairing same.

The heat receiving and heating fluids are caused to pass only through flues 28 and through passages 54 and 56 between and around the flues in close heat transferring relationship thereto; flow through other portions of the apparatus being prevented by baffles or blanketing devices such as deflector 74. Since it is desirable to maintain the same velocity of flow of the fluids on both sides of the heat conductant diaphragm through which heat is being transferred in the recuperator, it is preferred to so adjust the ratio between the sum of the cross sectional areas of the flues in one tier and the sum of the areas of the spaces between and around said flues as to maintain substantially the same velocity of flow of fluid through the flues and through the passages surrounding the flues.

In the recuperator design illustrated in the drawing, each W-shaped tube section is shown as occupying a 30° segment of the angular space surrounding the central opening 16. It will be understood, however, that the invention is not limited to the use of any particular number of sections 26 in a tier or to any particular number of tiers in a bank or nest, nor to any particular number of flues. The number of flues and the number of tiers making up the flues will depend primarily on the volume of oil or other fluid to be heated and/or on the amount of heat contained in the hot gases and vapors or other heating fluid.

There is no preferred manner of supporting the flues, or the tube nests and tiers making up the flues, within the shell. The flues may for example be supported within the shell by deflector brackets 82 projecting from the inner walls of the shell 10 immediately above the top dephlegmator tray 18 (see Fig. 1). Similarly the deflector 74 may be supported within the shell by simply resting brackets 84 on its outer periphery on the tops of the joints between connecting legs of the W-shaped sections making up the upper tiers of the flues 28. Each of the tiers A, B, C is supported in the structure and spaced from the tier immediately below it by the spacer bosses 60 forming an integral part of the W-shaped sections of which the tiers are composed. In order to avoid undue crowding of the disclosure only a few tiers and only a few of the spacers between the tiers have been shown.

As already indicated, the fluid to be heated is preferably passed through the recuperator in a direction which is in general countercurrent to the direction followed by the heat-

ing fluid in traversing the recuperator. One of the fluids, however, and preferably the heat receiving fluid, is forced to follow a long devious course in traversing the recuperator through paths which extend at right angles as well as countercurrent to the paths followed by the heating gases.

The above invention having been thus described what is claimed as new is:

1. A W-shaped tube section embodying in an integral compact structure lying in one plane, two outer converging legs, the diverging end of each of said legs being joined to the other by three successive return bends and by the connecting legs appurtenant thereto.

2. A W-shaped tube section embodying in an integral structure lying in one plane, three successive return bends with their appurtenant connecting legs and two outer converging legs each open at one end and connected at its other end to the two outside return bends, said two outside return bends forming the base of the structure and the converging open ends of said outer legs forming the top of the structure.

3. A W-shaped tube section embodying in an integral structure lying in one plane, two moderately bent converging outer legs of uniform length, one end of each of which is joined to the other by three successive return bends and by two inner connecting legs appurtenant thereto.

4. A W-shaped tube section embodying in an integral structure lying in one plane, two outer converging legs of uniform length, one end of each of which is joined to the other by three successive return bends and by two inner converging legs appurtenant thereto, said inner legs being of substantially equal but shorter length than said outer legs.

5. A W-shaped tube section embodying in an integral structure lying in one plane, three successive return bends with their appurtenant connecting legs and two outer converging legs each open at one end and connected at its other end to the two outside return bends, said two outside return bends forming the base of the structure and the open converging ends of said outer legs forming the top of the structure, all of said legs and bends being disposed in closely spaced relationship.

6. A tube section embodying in an integral structure lying in one plane, two outer legs of substantially equal length, one end of each of which is joined to the other by an inner connecting leg, the unconnected ends of said outer legs converging and having right angle bends formed thereon in closely spaced back to back relationship.

7. A W-shaped tube section embodying in an integral structure lying in one plane, three successive return bends with their appurtenant connecting legs, and two outer legs each open at one end and connected at its other

end to the two outside return bends, said two outside return bends forming the base of the structure and the open ends of said outer legs forming the top of the structure, and spacer 5 bosses extending laterally from said section.

8. A W-shaped tube section embodying in an integral structure lying in one plane, two outer converging legs of uniform length, one end of each being joined to the other by three 10 successive bends and by two inner converging legs appurtenant thereto, said inner legs being of substantially equal but shorter lengths than said outer legs, and tapped and plugged openings in the end of each of said 15 return bends.

9. A recuperator tube section embodying, in an integral structure lying in one plane and disposed in compact form within the area of an annulus segment, two outer converging legs each having a closed end joined to the other by appurtenant inner connecting legs and each having a free end, the axes of said legs converging substantially toward the center of the annulus, and each leg having a 25 substantially right angle bend, each bend faced back to back in closely spaced relation to the corresponding bend on the other leg.

10. A W-shaped tube section embodying in a structure lying in one plane, two outer legs 30 of substantially equal length one end of each of which is joined to the other by three successive return bends and by the connecting legs appurtenant thereto, the unconnected open ends of said outer legs having substantially right angle bends placed in spaced back to back relationship thereon, and bolt 35 ing ears formed on each right angle bend.

11. A tube section embodying in an integral structure lying in one plane, two outer legs 40 of substantially equal length one end of each of which is joined to the other by inner connecting legs appurtenant thereto, the unconnected open ends of said outer legs having substantially right angle bends placed in 45 back to back relationship thereon, and male and female joints formed respectively on the open ends of said outer legs for attachment to a corresponding section.

12. W-shaped tube section embodying in 50 an integral structure lying in one plane, two outer legs of substantially uniform length, each connected at one end to the other by three successive return bends and two shorter connecting legs appurtenant thereto and each 55 outer leg having at its open end a right angle bend faced in the opposite direction to the corresponding bend on the other leg, all of said structure being arranged to form a compact triangular shaped annulus section, the 60 two outer legs converging substantially toward the center of the annulus.

13. In heat interchanging apparatus, in combination, an outer closed cylindrical shell, and a plurality of integral heat 65 conductant uniformly-shaped flue sections con-

nected end to end to form a sinuous flue disposed in a plane at right angles to the longitudinal axis of said shell concentrically between the inner periphery of said shell and an axial passage through the same.

14. In heat interchanging apparatus, in combination, an outer closed cylindrical shell, a plurality of integral uniformly-shaped flue sections connected end to end to form a sinuous flue tier, a number of said tiers being 70 disposed in closely spaced parallel planes concentrically between the inner periphery of said shell and an axial manhole passage through the same, and return bends connecting adjacent pairs of said flue tiers.

15. In heat interchanging apparatus, in combination, an outer closed cylindrical shell, a plurality of integral uniformly-shaped flue sections connected end to end to form a sinuous flue disposed in a plane at 75 right angles to the longitudinal axis of the shell and concentrically between the inner periphery of said shell and a manhole passage along said longitudinal axis, fluid inlets and outlets respectively for said flue and 80 for passages surrounding said flue, and a deflector in said manhole passage for preventing fluid from by-passing the passages around said flue.

16. In heat interchanging apparatus, in combination, an upright closed cylindrical shell, a continuous heat conductant interchanger flue disposed concentrically in the annular space between the inner walls of said shell and a manhole passage extending 100 along the longitudinal axis of said shell, said flue comprising a number of superimposed, sinuous, horizontally lying flue tiers connected to each other by vertically placed return bends, and each tier in turn comprising 105 a plurality of uniformly shaped tube sections connected end to end.

17. In heat interchanging apparatus, in combination, a heat conductant diaphragm member comprising a plurality of integral 110 uniformly-shaped flue sections assembled end to end in parallel tiers, means connecting adjacent tiers in multiple to form a nest of annular cross-section disposed concentrically between the inner wall of a closed cylindrical shell surrounding said nest and an axial longitudinal manhole passage through said shell, a manhole opening in the end wall of said shell in line with said axial passage of sufficient area to pass said integral flue 115 sections and return bends, a closure for said manhole opening, a deflector mounted in said axial manhole passage, and separate inlets and outlets for fluids to said flue and to 120 passages through said nest surrounding said flue.

18. A combined dephlegmator and heat interchanger apparatus unit embodying, in combination, an upright closed cylindrical shell, a manhole opening in the top of said 125

shell, an axial manhole passage extending along the longitudinal axis of said shell between said manhole opening and a top tray of said dephlegmator, a heat conductant interchanger flue disposed concentrically in the space between the inner walls of said shell and said manhole passage and comprising a plurality of compactly arranged sinuous flow tiers, each tier being connected to the adjacent tiers by return bends, and each tier comprising a plurality of integral W-shaped flue sections connected end to end to form an annulus section, the legs of the flue section converging toward the center of the annulus, fluid inlets and outlets respectively to said flues and to passages surrounding said flues, and deflector means for forcing fluid to flow through rather than by-pass said passages.

19. In heat interchanging apparatus, in combination, an outer closed cylindrical shell and a continuous heat conductant inner flue disposed in the form of a nest of closely spaced connected parallel tiers concentrically between the inner periphery of said shell and an axial passage therein, each of said tiers comprising a plurality of integral uniformly shaped flue sections connected end to end to form an annulus section placed in a plane at right angles to said axial passage, the means connecting each pair of tiers comprising an integral uniformly shaped tubular return bend having right angle bends on the open ends of each of its appurtenant legs, each right angle bend faced in a direction at right angles to the axis of the return bend for attachment to the open ends of the respective tiers to be connected.

20. In heat interchanging apparatus, in combination, an outer closed cylindrical shell, a manhole opening in one end of said shell, a manhole passage extending from said opening along the inner longitudinal axis of the shell, and a plurality of uniformly shaped compact sinuous flues assembled in multiple within said shell into a nest of annular cross section disposed in readily accessible compact form concentrically in the space between the inner periphery of said shell and said manhole passage.

50 In testimony whereof I affix my signature.
DAVID G. BRANDT.
